to guarantee good distilled sewage to said plant of Libbey-Owens-Ford Glass Company and the means of this guarantee being provided to allow the glass to be cleaned and dried before being sent to the plant. The sewage plant is located in Toledo, Ohio, and is owned by the Toledo Sewerage and Water Board. The plant is located on the west side of the city of Toledo, Ohio, and is owned by the Toledo Sewerage and Water Board. The plant is located on the west side of the city of Toledo, Ohio, and is owned by the Toledo Sewerage and Water Board.

UNITED STATES PATENT OFFICE

JOHN L. DRAKE, OF TOLEDO, OHIO, ASSIGNOR TO LIBBEY-OWENS-FORD GLASS COMPANY, OF TOLEDO, OHIO, A CORPORATION OF OHIO

SYSTEM FOR SURFACING GLASS SHEETS

Application filed June 29, 1929. Serial No. 374,832.

The present invention relates broadly to the surfacing of glass sheets or other flat sheets or plates of material and more particularly to such a system wherein the grinding and polishing of the sheets or plates is performed in a straight-away operation.

The system herein provided is primarily designed for the continuous surfacing of sheet glass and consists of two substantially parallel tracks, one constituting the working track and the other the return track. Adapted to be mounted above the working track are a series of grinding and polishing units and suitable cars or tables are movable along this track to carry the glass sheets secured to the tops thereof beneath and in engagement with the grinding and polishing units. After the grinding and polishing operations have been completed, the glass sheets are removed from the cars or tables and the said cars or tables transferred to the return track along which they are moved to the starting end of the working track. The transfer means herein provided for transferring the cars or tables from one track to the other consists preferably of a rotatable transfer or turn table provided at one or both ends of the parallel tracks.

The primary object of the invention is the provision of novel means, preferably in the form of an operating car or dinkey, operable automatically to effect the transfer or removal of the work cars or tables from the working track onto the turn table in an effective and efficient manner with safety and ease of operation. Another object is the provision of means operable by the work cars or tables advancing along the working track for placing the operating car or dinkey in operation to effect movement thereof in the desired direction either forwardly or rearwardly. Another object is the provision of means for coupling the operating car or dinkey to and uncoupling it from the work cars or tables upon movement of said dinkey in a predetermined direction.

A further object of the invention is to provide means for automatically stopping the operating car or dinkey when it reaches a predetermined position during its forward or

rearward movement. A still further object is to provide means operable by the dinkey for effecting the rotation of the turn table after the work table has been moved thereon from the working track and for then automatically bringing said dinkey to a stop. Still another object is to provide means for preventing movement of the operating car or dinkey unless the turn table is properly positioned with the individual track sections thereon in alignment with the working track and return track.

Other objects and advantages of the invention will become more apparent during the course of the following description when taken in connection with the accompanying drawings.

In the drawings forming a part of this application and wherein like numerals are employed to designate like parts throughout the same, the following is

Fig. 1 is a diagrammatic top plan view of one end of the grinding and polishing system provided by the present invention.

Fig. 2 is a side elevation, partially in section, of the operating car or dinkey.

Fig. 3 is a section taken substantially on line 3-3 of Fig. 2.

Fig. 4 is a sectional view taken substantially on line 4-4 of Fig. 3 showing the magnetic brake partially broken away.

Fig. 5 is a side elevation of a portion of the operating car.

Fig. 6 is a section taken substantially on line 6-6 of Fig. 3.

Fig. 7 is a section taken substantially on line 7-7 of Fig. 1.

Fig. 8 is a detail view of the operating car safety switch, and

Fig. 9 is a wiring diagram showing the electrical wiring for the various parts of the system.

Referring to the drawings, there is employed in the present system the two main longitudinally extending parallel tracks 10 and 11, the track 10 constituting the working track and track 11 the return track. Adapted to be mounted above the working track 10 are a plurality of grinding and polishing machines (not shown) and movable along the

tracks 10 and 11 are a series of work cars or tables 12 supported upon wheels 13 rolling along said tracks. The tables 12 are preferably coupled together to form a continuous train during their travel along working track 10 and are adapted to carry glass sheets secured to the tops thereof to the left in the direction indicated by the arrow in Fig. 1, beneath the grinding and polishing machines referred to above. When the tables 12 reach the left hand end of working track 10 the glass sheets are removed therefrom, after which said tables are transferred to the return track 11 and carried therealong in the opposite direction to the starting end of working track 10.

The means herein provided for transferring the cars or tables 12 from the working track 10 to return track 11 at one end of the system and from the return track 11 to working track 10 at the opposite end of the system preferably includes a rotatable transfer or turn table 14, said table carrying the four individual track sections 15, 16, 17 and 18, the track sections 15 and 17 being parallel with one another while the track sections 16 and 18 are also parallel with one another and positioned at substantially right angles to the first mentioned track sections 15 and 17. Upon rotation of the turn table 14, the individual track sections thereon will be selectively brought into alignment or registry with the working and return tracks 10 and 11. The turn table is adapted to be rotated by means of a motor 19 driving through suitable reduction gearing a pinion 20 meshing with a ring gear 21 carried by said table.

Positioned outwardly of the turn table 14 at one side thereof is an auxiliary track 22 in alignment with the working track 10 and also with that particular individual track section on the turn table which happens to be in registry with the working track. The auxiliary track 22 is provided primarily to carry an operating car or dinkey 23 which comprises, as illustrated in Figs. 2 and 3, a truck 24 supported upon wheels 25, said dinkey being operated from a motor 26 supported upon the truck. The shaft 27 of motor 26 is suitably connected with a shaft 28 carrying a worm 29 meshing with a worm gear 30 secured to horizontal shaft 31 journaled in the opposite side walls of casing 32. Mounted in alignment with shaft 31 is a shaft 33 connected thereto by means of a suitable coupling 34, said shaft 33 being journaled in the opposite side walls of a casing 35 and carrying within said casing a spur gear 36 meshing with a drive pinion 37 keyed to one of the axles 38 of the dinkey and which axle carries supporting wheels 25. Thus, upon operation of the motor 26, the axle 38 will be positively driven through the mechanism above described to effect the desired movement of the dinkey.

It is, of course, desirable upon stopping of the motor 26 that the dinkey be brought to a relatively quick stop and to accomplish this, there may be provided a magnetic brake of the type illustrated in Fig. 4 and designated 39 in its entirety by the numeral 39. The brake 39 comprises a brake wheel or drum 40 mounted upon and secured to the axle 38 by means of a key 41. The brake 39 further includes a horizontal base member 42 secured to the bottom of the dinkey truck 24 and having pivoted thereto at one end, as indicated at 43, a depending shoe lever 44 carrying a shoe 45 adapted to engage brake wheel 40. Carried adjacent the opposite end of base member 42 is a depending field member 46 also pivoted to said base member as at 47, and carrying a coil or magnet 48. Also pivoted to the base member 42 is a shoe lever 49 carrying the shoe 50 adapted to engage brake wheel 40 opposite brake shoe 45. Carried at the lower end of shoe lever 49 is an armature lever 51 positioned opposite the coil or magnet 48 and having connected thereto one end of a compression spring 52 which passes through the field member 46 and bears at its outer end against a spring gland 53. Connecting the lower ends of the shoe lever 44 and field member 46 is a pull rod 54, pivoted to the latter as at 55, the opposite end of said rod being threaded and extending through a bearing 56 pivoted as at 57 to shoe lever 44. The pull rod 54 is held in proper position by two nuts 58 and 59 threaded thereupon at opposite ends of bearing 56.

The magnetic brake 39 is connected in series with the motor 26 on dinkey 23 and when the power is on and said motor is operating, the brake is released and when the power is shut off to stop the motor the brake is set. For instance, when it is desired to move the dinkey 23 forwardly, the motor 26 thereof is placed in operation and simultaneously the coil or magnet 48 will be energized. The energization of this coil acting in conjunction with compression spring 52 will tend to move the field member 46 and shoe lever 49 simultaneously in opposite directions. In other words, the field member will be drawn inwardly to rock shoe lever 44 about its pivot 43 to move shoe 45 out of engagement with wheel 44, while the shoe lever 49 will be rocked outwardly about its pivot 47 to move shoe 50 out of engagement with wheel 40. On the other hand, when the motor 26 is stopped, the coil or magnet 48 will be de-energized and the compression spring 52 will then act to force the shoe lever 49 inwardly and the field member 46 outwardly which will draw the shoe lever 44 inwardly into engagement with the brake wheel or drum 40 and thus bring the dinkey to a stop.

According to the present invention, the operating car or dinkey 23 is adapted, as will be later more fully explained, to travel to the

right from auxiliary track 22 across the turn table 14 and engage the first or end work table 12 on working track 10, after which the travel of the dinkey is reversed to pull the work table into proper position on the turn table, whereupon the dinkey is adapted to release the work table and then return to its position upon the auxiliary track 22. Simultaneously with the moving of the work table from working track 10 onto turn table 14, one of the work tables is adapted to be pushed from the turn table onto the return track 11 and this latter operation may be accomplished by the provision of an overhead pusher designated in its entirety by the number 60, and comprising preferably an endless horizontal chain driven from a motor 61 through the intermediary of suitable reduction gearing and carrying one or a plurality of pusher elements (not shown) which engage the rear end of the work table and push the same from the turn table onto the return track.

As brought out above, the transfer of the work cars or tables from working track 10 to return track 11 is adapted to be effected automatically and without any manual aid or assistance. To this end, there are positioned between the rails of the working track 10 adjacent the turn table 14, the three switches 62, 63 and 64, said switches being positioned in longitudinal alignment with one another, with the switches 62 and 63 relatively close together. Also positioned between the rails of the auxiliary track 22 are two similar switches 65 and 66, said switches being in longitudinal alignment with the previously mentioned switches 62, 63 and 64. There is further positioned outwardly of but adjacent to the working track 10, a switch 67. The several switches referred to above are preferably of the same construction and each is adapted to be controlled, as shown in Figs. 5 and 7, by the provision of a starwheel or the like 68 having a plurality of radiating actuating fingers 69. The switches 62, 64, 66 and 67 are connected in series with the motor 26 and magnetic brake 39 carried by dinkey 23 while the switch 63 is connected in series with the motor 61 for the overhead pusher 60 and the switch 65 is connected in series with the motor 19 for turn table 14.

In operation and upon movement of the work tables 12 to the left along working track 10, the depending plate 70 (Fig. 7) carried at the forward end of the work table, will engage the star-wheel 68 of switch 62 and rotate said wheel in a manner to close said switch. This will complete an electrical circuit through the dinkey motor 26 and magnetic brake 39 to start the dinkey forwardly to the right across the turn table 14 and such forward movement of the dinkey will continue until the switch plate 71 (Fig. 5) carried upon the outer side of the dinkey

and pivoted thereto as at 72 engages the star-wheel 68 of a switch 67 and actuates said switch to break the circuit through the dinkey motor 26 and magnetic brake 39. As above stated, upon the shutting off of motor 26, the magnetic brake 39 will be set to bring the dinkey to a stop, this position of the dinkey being indicated by the broken lines to the right in Fig. 1.

During the forward movement of the dinkey, the work table 12 is continuously moving to the left along the working track 10 and will next actuate switch 63 which will complete the circuit through motor 61 and start the operation of the overhead pusher 60 to remove a work table from the turn table onto the return track 11, any suitable means being provided for stopping the overhead pusher when it reaches a predetermined position. Upon continued movement of work table 12 along working track 10, the said table will actuate switch 64 which will again close or complete the circuit through the dinkey motor 26 and magnetic brake 39 to start the dinkey rearwardly. Just prior to the operation of switch 64, however, the hook 73 (Fig. 2) formed at the forward end of lever 74 pivoted intermediate its ends as at 75 to the dinkey, is adapted to hook under the forward end of the work table 12 so that upon rearward movement of the dinkey, the table 12 will be pulled therewith onto the turn table. When the work table 12 reaches a predetermined position upon the turn table, the opposite or rear end of the lever 74 which carries a roller 76 is adapted to ride up on a cam member 77 to rock said lever about its pivot and lower the hook 73 out of engagement with the table so as to permit said table to come to rest upon the turn table while the rearward movement of the dinkey is continued.

As the dinkey 23 passes rearwardly from the turn table 14, the depending switch lug 78 (Fig. 6) pivoted to the rear end of dinkey as at 79, will engage the star-wheel 68 of switch 65 and rotate the same so as to close said switch 65 which will complete the circuit through the turn table motor 53 and effect the rotation of said turn table, a quarter of a revolution, suitable means being provided for stopping the turn table when it reaches a predetermined position. Upon continued rearward movement of the dinkey, the pivoted lug 78 will actuate switch 66 to again break the circuit through the dinkey motor and magnetic brake so as to bring said dinkey to a stop. When it is desired to move another car or table from the working track 10, the above cycle of operations is repeated.

The invention also embodies means for preventing the operation of the dinkey 23 unless the individual track sections on the turn table 14 are in proper alignment with the working track and return track. To this

end, there is provided a fixed switch 80 shown in Fig. 8, and which switch is also connected in series with the dinkey motor 26 and magnetic brake 39, said switch being controlled by the pivoted arm 81 having a laterally projecting lug or pin 82. Carried by the turn table 14 is a vertically disposed plate 83 having a bevelled edge 84. The switch 80 is normally opened, but when the turn table is rotated and brought to a stop in the proper position with respect to the working and return tracks 10 and 11, the pin 82 carried by switch plate 81 will ride up on the bevelled edge 84 of plate 83 so as to close the switch 80, and upon closing of said switch, the dinkey can then be operated upon the closing of either of the dinkey start switches 62 or 64. The switch 80 is of the double acting type as will be later more fully explained. The switch 80 may also be connected in the series with the overhead pusher, if desired, to prevent operation thereof unless the turn table 14 is properly positioned with respect to the working and return tracks.

Referring more particularly to the wiring diagram illustrated in Fig. 9, it is believed that the operation of the various parts of the system will be made more clear. Each of the switches 62, 64, 66 and 67 is of the six-point type or, in other words, each includes six contact points and a single rotatable switch arm. The three contacts 86, 87 and 88 of switch 62 are connected to the positive main 89 by the wires 90, 91 and 92 respectively. Leading from the other three contacts 93, 94 and 95 of said switch are the wires 96, 97 and 98 connected to the three contacts 99, 100 and 101 respectively of the dinkey stop switch 67, while leading from the contact 102 of switch 67 is a wire 103, running to the contact 104 of safety switch 80 which, as above stated, is of the double acting type including the four contact points 104, 105 and 106 and 107 and a pair of pivoted switch blades 108 and 109 operable as a unit. Leading from the contacts 110 and 111 of switch 67 are wires 112 and 113 connected to wire 103. Running from contact 105 of safety switch 80 is a wire 114 connected to motor 26 and also to the magnetic brake 39 by means of a wire 115. The switch 64 includes the three contacts 116, 117 and 118 connected to the positive main 89 by wires 119, 120 and 121 respectively. Connected to and leading from the contacts 122, 123 and 124 of said switch 64, are the wires 125, 126 and 127 respectively running to the contacts 128, 129 and 130 of switch 66. Leading from the contact 131 of switch 66 is a wire 132 connected to contact 107 of safety switch 80 and leading from the opposite contact 106 of said safety switch is a wire 133 connected to a wire 134 which leads to both the motor 26 and magnetic brake 39. Leading from the contacts 135 and 136 of

switch 66, are wires 137 and 138 respectively, connected to wire 132. Leading from the motor 26 and connected to the negative main 139 are the two wires 140 and 141, while two wires 142 and 143 lead from the magnetic brake 39 to negative main 139. The switches 62, 64, 66 and 67 are provided with the rotatable switch arms 144, 145, 146 and 147 respectively, each of which is movable to simultaneously engage two oppositely disposed contacts.

In operation, and when the switch arms 144 to 147 of switches 62, 64, 66 and 67 are in the positions indicated by the full lines in Fig. 9, and the safety switch 80 is closed, the dinkey 23 is travelling in its rearward direction to draw or pull one of the work tables 12 from the working track 10 onto the turn table 14. In other words, the switch 64 has just been actuated by the work table to complete the circuit through the dinkey motor 26 and magnetic brake 39. The electric current will then enter through the positive main 89 and pass through wire 119 to the switch arm 145 of switch 64 and then through wire 127 to the switch arm 146 of switch 66, then through wire 132, through safety switch 80, wire 133, to wire 134, and from wire 134 to both the motor 26 and magnetic brake 39, the current passing from the motor and brake 26 and 39 through the wires 140, 141, and 142, 143 respectively to the negative main 139. When the dinkey 23 actuates the switch 66 to bring said dinkey to a stop, the switch arm 146 thereof will be moved to the broken line position indicated in Fig. 9, whereupon the circuit will be broken as the electric current will no longer be permitted to pass through this switch.

After the turn table has been rotated and the next work table 12 engages switch 62, the switch arm 144 will be rotated to the position indicated in Fig. 9 to engage contacts 88 and 93 respectively, to complete the circuit and start the forward movement of the dinkey. When such circuit is completed, the electric current will enter through the positive main 89, pass through wire 92, through switch arm 144 of switch 62, then through wire 96, through switch arm 147 of switch 67, through wire 103 to safety switch 80, through wire 114 to the motor 26 and also through wire 115 to magnetic brake 39, and from the motor and magnetic brake to the negative main 139. The forward movement of the dinkey will be continued until it actuates switch 67 to rock the switch arm 147 thereof into the broken line position indicated in Fig. 9, whereupon the circuit just described will be broken as the electric current will no longer be permitted to pass through switch 67.

Upon continued movement of the work table, the switch 64 will be actuated to again complete the circuit and the switch arm

145 thereof will be moved to engage contacts 117 and 123. The electric current can then enter from the positive main through wire 120, pass through the switch arm 145
 5 of switch 64 to wire 126, then through the switch arm 146 of switch 66, through wires 137 and 132 to safety switch 80, from safety switch through wire 133 to wire 134 which leads to both the motor 26 and magnetic
 10 brake 39. Upon continued rearward movement of the dinkey 23, the switch 66 will again be actuated to move the switch arm 146 to engage contacts 128 and 136 whereby the circuit will again be broken to bring the
 15 dinkey to a stop. The above cycle of operations is simply repeated during the removal of each table 12 from the working track 10. The electrical wiring arrangement for the operation of the turn table 14 and overhead
 20 pusher 60 has been omitted for the sake of simplicity. Since the dinkey is continuously moving forwardly and rearwardly, the electric wires associated therewith may be contained within a cable 148 connected with
 25 the dinkey at one end and wound upon a reel 149 operated by motor 150. This motor is adapted to be continuously rotated in a direction tending to wind the cable 148 upon reel 149 during the forward movement of the
 30 dinkey, the cable is unwound against the action of said motor.

Those features of the present invention disclosed herein but not specifically claimed are more fully described and claimed in my
 35 copending application filed June 29, 1929, Serial No. 374,881.

It is to be understood that the form of the invention herewith shown and described is to be taken as the preferred embodiment of
 40 the same, and that various changes in the shape, size and arrangement of parts may be resorted to without departing from the spirit of the invention or the scope of the subjoined claims.

45 I claim:

1. In a system of the class described, a pair of substantially parallel tracks, tables movable along the tracks, transfer means between the tracks at their ends, means for removing
 50 the tables from one of said tracks to a position upon said transfer means, and means operable automatically for bringing said table removing means to a stop when it reaches a predetermined position with respect to the tables to be transferred.

2. In a system of the class described, a pair of substantially parallel tracks, tables movable along the tracks, transfer means between the tracks at their ends, means for removing the tables from one of said tracks to a position upon said transfer means, means for moving said table removing means forwardly and rearwardly, and means operable
 60 automatically for bringing the same to a stop

when it reaches predetermined positions in its forward and rearward travel.

3. In a system of the class described, a pair of substantially parallel tracks, tables movable along the tracks, transfer means
 70 between the tracks at their ends, means for removing the tables from one of said tracks to a position upon said transfer means, means for moving said table removing means forwardly and rearwardly, and means operable automatically by the movement of said tables for starting the forward and rearward movement thereof.

4. In a system of the class described, a pair of substantially parallel tracks, tables movable along the tracks, transfer means between the tracks at their ends, means for removing the tables from one of said tracks to a position upon said transfer means, means for moving said table removing means forwardly and rearwardly, means operable automatically by the movement of the table removing means for bringing the same to a stop when it reaches a predetermined position with respect to the tables to be transferred, and means operable automatically by the movement of said tables for starting the forward and rearward movement of said table removing means.

5. In a system of the class described, a pair of substantially parallel tracks, tables movable along the tracks, transfer means between the tracks at their ends, means for removing the tables from one of said tracks to a position upon said transfer means, means for moving said table removing means forwardly and rearwardly, means operable automatically by the movement of the table removing means for bringing the same to a stop when it reaches predetermined positions in its forward and rearward travel, and means operable automatically by the movement of said tables for starting the forward and rearward movement of the table removing means.

6. In a system of the class described, a pair of substantially parallel tracks, tables movable along the tracks, transfer means between the tracks at their ends, means for removing the tables from one of said tracks to a position upon said transfer means, means for moving said table removing means forwardly, means operable automatically to bring the same to a stop when it reaches a predetermined position with respect to the tables to be transferred, means for automatically coupling the table removing means and table together, means operable automatically to reverse the direction of movement of the table removing means so as to move the table therewith, means for automatically uncoupling the table removing means from the table when said table reaches a predetermined position upon the transfer means, and means operable automatically to stop the movement

of the table removing means in a position remote from the transfer means.

7. In a system of the class described, a pair of substantially parallel tracks, tables movable along the tracks, transfer means between the tracks at their ends, means for removing the tables from one of said tracks to a position upon said transfer means, means for moving said table removing means forwardly, means operable automatically upon movement of the table removing means to bring the same to a stop when it reaches a predetermined position with respect to the tables to be transferred, means for automatically coupling the tables removing means and tables together, means operable automatically upon movement of the tables, to reverse the direction of travel of the table removing means to pull said table therewith, means for automatically uncoupling the table removing means from the table when said table reaches a predetermined position upon the transfer means, and means operable automatically by the movement of the table removing means for bringing the same to a stop in a position remote from said transfer means.

8. In a system of the class described, a pair of substantially parallel tracks, tables movable along the tracks, transfer means between the tracks at their ends, means operable automatically for removing the tables from one of said tracks to a position upon said transfer means, and means for preventing operation of said table removing means unless the transfer means is properly located with respect to the parallel tracks.

9. In a system of the character described, a pair of substantially parallel tracks, tables movable along the tracks, a turn table between the tracks at their ends for transferring the tables from one track to the other track, and an operating car automatically operable to move the tables from one of said tracks to a position upon said turn table.

10. In a system of the character described, a pair of substantially parallel tracks, tables movable along the tracks, a turn table between the tracks at their ends for transferring the tables from one track to the other track, an operating car for moving the tables from one of said tracks to a position upon said turn table, and means operable automatically for bringing the operating car to a stop when it reaches a predetermined position with respect to the tables to be transferred.

11. In a system of the character described, a pair of substantially parallel tracks, tables movable along the tracks, a turn table between the tracks at their ends for transferring the tables from one track to the other track, an operating car for moving the tables from one of said tracks to a position upon said turn table, means for moving said operating car forwardly and rearwardly, and

means operable automatically for bringing the same to a stop when it reaches predetermined positions in its forward and rearward travel.

12. In a system of the character described, a pair of substantially parallel tracks, tables movable along the tracks, a turn table between the tracks at their ends for transferring the tables from one track to the other track, an operating car for moving the tables from one of said tracks to a position upon said turn table, means for moving said operating car forwardly and rearwardly, and means operable automatically by the movement of said tables for starting the forward and rearward movement thereof.

13. In a system of the character described, a pair of substantially parallel tracks, tables movable along the tracks, a turn table between the tracks at their ends for transferring the tables from one track to the other track, an operating car for moving the tables from one of said tracks to a position upon said turn table, means for moving said operating car forwardly and rearwardly, means operable automatically by the movement of the operating car for bringing the same to a stop when it reaches a predetermined position with respect to the tables to be transferred, and means operable automatically by the movement of said tables for starting the forward and rearward movement of said operating car.

14. In a system of the character described, a pair of substantially parallel tracks, tables movable along the tracks, a turn table between the tracks at their ends for transferring the tables from one track to the other track, an operating car for moving the tables from one of said tracks to a position upon said turn table, means for moving said operating car forwardly and rearwardly, means operable automatically by the movement of said operating car for bringing the same to a stop when it reaches predetermined positions in its forward and rearward travel, and means operable automatically by the movement of said tables for starting the forward and rearward movement of said operating car.

15. In a system of the character described, a pair of substantially parallel tracks, tables movable along the tracks, a turn table between the tracks at their ends for transferring the tables from one track to the other track, an operating car for moving the tables from one of said tracks to a position upon said turn table, means for moving said operating car forwardly, means operable automatically to bring the same to a stop when it reaches a predetermined position with respect to the table to be transferred, means for automatically coupling the operating car and table together, means operable automatically to reverse the direction of movement of the

operating car so as to move the table therewith, means for automatically uncoupling the operating car and table when said table reaches a predetermined position upon the turn table, and means operable automatically to stop the movement of said operating car in a position remote from said turn table.

16. In a system of the character described, a pair of substantially parallel tracks, tables movable along the tracks, a turn table between the tracks at their ends for transferring the tables from one track to the other track, an operating car for moving the tables from one of said tracks to a position upon said turn table, means for moving said operating car forwardly, means operable automatically upon movement of the operating car to bring the same to a stop when it reaches a predetermined position with respect to the table to be transferred, means for automatically coupling the operating car and table together, means operable automatically upon movement of the table to reverse the direction of travel of said operating car to pull said table therewith, means for automatically uncoupling the operating car and table when said table reaches a predetermined position upon said turn table, and means operable automatically by movement of the operating car for bringing the same to a stop in a position remote from said turn table.

17. In a system of the character described, a pair of substantially parallel tracks, tables movable along the tracks, a turn table between the tracks at their ends for transferring the tables from one track to the other track, said turn table having a plurality of individual track sections adapted to align with the parallel tracks, an operating car automatically operable to move the tables from one of said parallel tracks to a position upon one of the individual track sections of the turn table, and means for preventing operation of the operating car unless the individual track sections on the turn table are in proper alignment with the parallel track sections.

Signed at Toledo, in the county of Lucas and State of Ohio, this 21st day of June, 1929.

JOHN L. DRAKE.
